UNITED STATES PATENT OFFICE

FRANK T. COPE, OF SALEM, OHIO, ASSIGNOR TO THE ELECTRIC FURNACE COMPANY,
OF SALEM, OHIO, A CORPORATION OF OHIO

CONTINUOUS BAR-HEAT-TREATING FURNACE

Application filed May 8, 1928. Serial No. 276,073.

The invention relates to heat treating furnaces and more particularly to a continuous furnace for the heating or heat treatment of bars and the like.

5 The object of the improvement is to provide a furnace in which elongated bars and the like may be continuously passed therethrough for heating or heat treatment, skid shoes being provided for carrying the bars through 10 the furnace, whereby a non-buckling carrying means is provided, and abrasion or scratching of the bars is eliminated.

The above and other objects may be accomplished by providing spaced skid rails 15 through the furnace, skid shoes being slidably mounted upon the rails and provided with means for advancing the same through the furnace chamber, the bars to be heated or heat treated being inserted at one end of 20 the furnace at right angles to the rails, and placed upon the skid shoes, means being provided at the other end of the furnace for pushing the bars out of the furnace.

An embodiment of the invention is illustrated in the accompanying drawings, in which—

Figure 1 is a plan sectional view of the improved furnace taken substantially on the line 1—1, Fig. 2; and

30 Fig. 2, a vertical sectional view through the furnace taken substantially on the line 2—2, Fig. 1.

Similar numerals refer to similar parts throughout the figures of the drawings.

35 The furnace is indicated generally at 1, provided with suitable refractory lining 2 and supported upon the beams 3. A suitable reinforcing structure of channel structural members, as shown at 4, may be provided 40 around the exterior of the furnace in usual manner.

The furnace chamber 5 may be substantially low in height, as best shown in Fig. 2, and is of a length and width to accommodate the 45 bars to be heated or heat treated and to give them sufficient travel through the furnace to accomplish the proper treatment thereof.

The furnace may be heated by electric resistors, as illustrated in the drawing, in which 50 case spaced piers 6 may be located upon the

floor and provided at their side faces with electric resistance elements, as shown at 7.

The upper edges of these piers may be covered as by the caps 8 of heat resisting alloy or the like, and certain of the piers may carry 55 skid rails 9, which may also be formed of heat resisting alloy, and which are preferably of channel cross sectional shape, and have upturned flanges as best illustrated in Fig. 2.

Supporting or bridging plates 10 may be 60 supported upon the piers carrying the skid rails and extending transversely between adjacent rails at the feed and discharge sides of the furnace. These bridging plates are located slightly below the level of the top of the 65 skid shoes and serve to direct a bent bar across the next row of shoes when the bar is being pushed into or out of the furnace. Otherwise a bent bar might hang down and strike a 70 pier wall or rail in being pushed through the furnace.

Skid shoes 11, substantially cylindrical in form and of any suitable and desirable material, are adapted to be slidably moved upon the skid rails within their upturned flanges and 75 are therefore rotatable therein. These shoes are of sufficient length to properly transversely space the bars under treatment, as shown at 12.

Referring to Fig. 1, it will be seen that the 80 skid rails extend outwardly through the entrance or charging side of the furnace, so that the shoes 11 may be placed thereon and moved into the furnace in unison as by a plurality of pushers 13, all of which may be simultaneously operated, in any suitable manner, from an operating shaft 14, which may be driven by a motor 15 through a reduction gearing or the like, as indicated generally at 16.

As each set of shoes is moved into the charging position, a bar 12, to be treated, is inserted endwise into the furnace and positioned upon the shoes in the position indicated at A in Fig. 1.

For this purpose, a charging opening 17 is 85 provided in one end of the furnace, adapted to be normally closed as by the door 18 to prevent heat loss. This charging of the bars may be accomplished in any suitable manner, and as shown in Fig. 1, the bar may be placed 100

upon a rail 19, located adjacent to and in alignment with the charging opening 17, and a pusher 20, operated by any suitable mechanism, may be reciprocated upon said rail to push the bar into the furnace, the bar being rollably engaged by the shoes 11, to the position shown at A.

As each new set of skid shoes is placed in position upon the entrance ends of the rails and 10 moved into the furnace, all of the skid shoes within the furnace will be moved forwardly step by step, thus intermittently advancing the bars under treatment toward the discharge end of the furnace. As each bar 15 reaches the discharge position indicated at B, the discharge door 21 may be opened and the bar discharged through the opening 22.

This may be accomplished by means of a pusher 23, adapted to enter the opposite side 20 of the furnace, through the opening 24 and to be projected entirely through the furnace, engaging the bar 12, which is in the discharge position, and forcing the same out through the discharge opening 22.

25 Straightening rolls, pinch rolls, or other pull-out device may, if desired, be located adjacent to the discharge opening 22 for carrying the bars away from the discharge point.

The pusher 23, the same as the pusher 20, 30 may be reciprocated by any suitable means, such as the drawbench 25, and will be returned to its initial position after each operation.

In order to carry the skid shoes away from 35 the exit side of the furnace, and return them to the entrance side thereof, the rails 11 may extend through the exit side of the furnace and communicate with downwardly inclined troughs or rails 26, by means of which the 40 shoes will be carried by gravity on to a conveyer chain or belt 27 driven by any suitable means, such as the motor 15, and adapted to convey the skid shoes beneath the furnace and return them to the starting point.

45 From the above it will be obvious that the bars are rolled on to and off of the skid shoes in charging and discharging the furnace, thus obviating scratching or abrasion of the surfaces of the bars. As the bars remain stationary relative to the shoes, while the same 50 are successively advanced through the furnace, there is no buckling of the bars during the pushing operation.

With this form of furnace, bars of considerable length may be accommodated in a furnace of comparatively small proportions, as it is only necessary that the length of the furnace be sufficient to accommodate the bars, and the bars being moved transversely 60 through the furnace, the width of the furnace may be only sufficient to permit of the proper duration of heating or heat treating of the bars.

I claim:

55 1. A bar furnace, spaced skid rails within

the furnace, cylindric skid shoes slidably and rotatably mounted upon the rails, means for charging bars longitudinally upon the shoes, means for moving the shoes transversely through the furnace and means for discharging 70 the bars from the shoes.

2. A bar furnace, spaced skid rails within the furnace, cylindric skid shoes slidably and rotatably mounted upon the rails, means for charging bars longitudinally upon the shoes, 75 means for moving the shoes transversely through the furnace and means for discharging the bars longitudinally from the shoes.

3. A bar furnace, spaced skid rails within the furnace, cylindric skid shoes slidably 80 and rotatably mounted upon the rails, means for charging bars longitudinally upon the shoes, means for moving the shoes transversely through the furnace, means for discharging the bars from the shoes, and means for returning the shoes to the entrance side of the furnace.

4. A bar furnace, spaced channel shaped skid rails within the furnace having upturned flanges, cylindric skid shoes slidably 90 and rotatably mounted on the channel rails for slidable movement longitudinally of the channel rails and for rotatable movement between the flanges thereof, means for longitudinally charging bars transversely of the 95 rails upon the shoes, means for slidably moving the shoes longitudinally of the rails through the furnace for moving the bars transversely through the furnace, and means for discharging the bars from the furnace. 100

5. A bar furnace having a charging opening and a discharging opening, spaced skid rails within the furnace, bridging plates extending transversely between adjacent rails at the charging and discharging sides of the 105 furnace, means for charging bars longitudinally into the furnace and positioning them upon the rails, means for moving the bars transversely upon the rails, through the furnace, and means for discharging the bars longitudinally from the furnace. 110

6. A bar furnace having a charging opening and a discharging opening, spaced skid rails within the furnace, bridging plates extending transversely between adjacent rails 115 at the charging and discharging sides of the furnace, the bridging plates being located slightly below the level of the top of the skid rails for directing a bar from one skid rail to another when being charged or discharged, means for charging bars longitudinally into the furnace and positioning them upon the rails, means for moving the bars transversely upon the rails, through the furnace, and means for discharging the bars longitudinally from the furnace. 120

7. A bar furnace having a charging opening and a discharging opening, spaced piers within the furnace, skid rails mounted on certain of said piers, bridging plates extend- 130

ing transversely between adjacent rails at the charging and discharging sides of the furnace and supported upon said piers, means for charging bars longitudinally into the furnace and positioning them upon the rails, means for moving the bars transversely upon the rails, through the furnace, and means for discharging the bars longitudinally from the furnace.

10 In testimony that I claim the above, I have hereunto subscribed my name.

FRANK T. COPE.
